UNITED STATES PATENT OFFICE.

JULIUS J. DRAWE, OF NEW ORLEANS, LOUISIANA.

STOCK-SAMPLER.

No. 892,943.

Specification of Letters Patent.

Patented July 7, 1908.

Application filed July 5, 1907. Serial No. 382,278.

To all whom it may concern:

Be it known that I, JULIUS J. DRAWE, a citizen of the United States, residing at New Orleans, in the parish of Orleans and State of Louisiana, have invented certain new and useful Improvements in Stock - Samplers; and I do hereby declare the following to be a full, clear, and exact description of the invention, such as will enable others skilled in the art to which it appertains to make and use the same.

This invention relates to improvements in devices for sampling stock where it is desired to get a true sample of the contents of a tank or vat for its full depth, and while the present invention may be used in other relations, it is particularly designed for use as a soap stock sampler.

Broadly speaking, the invention consists of a suitably shaped box member, which, for illustration, may be shown in the form of a trough open at both ends and along one side, the same coöperating with a longitudinal slide to close the open side, with a flexible gate carried by said slide adapted to be forced beneath the contents of the box or trough to close the lower end of the trough, and thus retain the contents therein when the same is withdrawn from the vat or tank.

While the invention is not restricted to the exact details shown and described, still for the purpose of disclosure, reference is had to the accompanying drawings illustrating a practical embodiment of the invention, in which like letters designate the same parts in the several views, and in which—

Figure 1 is a front elevation of the trough member showing the slide and the flexible gate closed. Fig. 2 is a similar view to Fig. 1, but showing the slide elevated with the gate in its open position, the view being shown broken away at the upper end. Fig. 3 is a cross section on the line 3—3 of Fig. 1. Fig. 4 is a fragmentary longitudinal section through the lower end of the trough member showing the slide in its lowermost position with the flexible gate in its closed position, and Fig. 5 is a fragmentary view of the rear wall of the trough showing a handle applied thereto for manipulating the trough member.

For the purpose of brevity, the term "trough member" is intended to cover any suitably shaped box or casing open at one side, and in the drawings this is illustrated at 1, as a rectangular elongated member,

preferably of metal open along one side, and the walls adjacent said open side terminating in a bent-over portion 2, forming longitudinal guideways for a slide 3, preferably of metal, and longitudinally corrugated, as shown more clearly at 4, Fig. 3, the corrugations being intended to form a lateral truss for the metallic slide to give it more rigidity and stiffness. This slide 3, at its edges, terminates in bent-over portions 5, adapted to coöperate with the longitudinal guideways 2 forming a sliding connection therewith.

6^a designates bands or strips passing around the body of the trough and over the slide for the purpose of retaining the parts rigidly in position to allow the device to be properly handled.

The side walls of the lower end of the trough member are cut away and curved downwardly, as at 6, and suitable internal guideways are formed around these curved edges. In the drawings, these guideways are illustrated as comprising the inturned flanges 7.

At the lower end of the slide 3 there is secured in any suitable manner a flexible gate 8, preferably of metal, which gate coöperates with the flanges 7 upon a downward movement of the slide to flex the said gate into a curve, and thereby close the lower opening of the trough. The upper end of the slide may be provided with a handle 9, and similarly a handle 10, Fig. 5, may be attached to the rear wall of the trough 1.

Preferably at the upper end of the trough there is pivoted a lever 11. This lever is provided with an elongated slot 12, coöperating with a pin 13 on the slide, so that the movements of the lever will operate the slide in opposite directions.

In operation, it will be seen that the device is forced or dropped through the soap stock or other contents of a vat, vessel or tank in its open position, as shown in Fig. 2. When the bottom of the vessel is reached, the lever 11 is thrown down, forcing the slide 3 downwardly, and the slide 3 similarly forces the flexible gate 8, in engagement with the flanges 7, around the flanges, flexing the gate in a curve, and closing the bottom opening of the trough member, as indicated in Figs. 1 and 4. The device being now withdrawn an accurate sample of the contents of the vessel may be procured. If the matter is too solid and will not flow or slip out of the bottom of the device after it has been with-

drawn from the tank and the slide moved to open the gate, then the lever 11 may be thrown off the pin 13 and the whole slide withdrawn, the guideways 2 being suitably formed in bending to allow of the passage of the flexible gate 8 therethrough, thus exposing the full contents and giving a perfect visible sample of the stock.

What I claim is:—

10. 1. The combination with a trough shaped member having an open lower end and an open side, a longitudinal slide for said open side, and means carried at the lower end of said slide for closing the lower end of said trough comprising a flexible gate, substantially as described.
20. 2. The combination of a trough shaped member open at its lower end and having an open side, a slide for said open side, a flexible gate carried by said slide and operating to close said lower end, and a lever pivoted to said trough and engaging said slide to operate same longitudinally of said trough, substantially as described.
30. 3. The combination of a trough provided with an open side extending longitudinally thereof and its sides terminating at their lower end in a downward curve, guiding means adjacent the curved opening at the lower end of said trough, a longitudinal slide for closing said open side, and a gate of flexible metal carried at the lower end of said slide and coöperating with said guiding means to assume the shape of said curved open end and form a gate therefor to close same, substantially as described.
35. 4. The combination of a trough member

formed of metal, open at its lower end and also open on one side, the walls of said trough adjacent said open side terminating in bent over portions forming internal guideways, and said side walls terminating at their lower ends in flanged downwardly-curved portions, a metallic longitudinally-corrugated slide provided with bent-over portions coöperating with said internal guideways, a gate of flexible metal carried at the lower end of said slide and engaging said flanged guideways to close said lower end upon downward movement of said slide, and means for operating said slide, substantially as described.

5. The combination with a metallic trough shaped member having an open curved lower end and an open side, guideways extending longitudinally of said trough member at the open side thereof, guideways formed at the curved open end of said trough, a slide coöperating with said longitudinal guideways, a flexible metallic gate carried by said slide and coöperating with said curved guideways to control the opening at said lower end, bands encircling said trough and slide to hold said device rigidly assembled, a pin carried by said slide, a lever secured to said trough member and provided with an elongated slot engaging said pin, a handle for said slide, and a handle for said trough, substantially as described.

In testimony whereof, I affix my signature, in presence of two witnesses.

JULIUS J. DRAWE.
